CLAIM

The ornamental design for the hook for hedge trimmer, as shown and described.

DESCRIPTION

FIG. 1 is a perspective view of a hook for hedge trimmer of the present invention;

FIG. 2 is a front view of the hook for hedge trimmer;

FIG. 3 is a back view of the hook for hedge trimmer;

FIG. 4 is a right side view of the hook for hedge trimmer;

FIG. 5 is a left side view of the hook for hedge trimmer;

FIG. 6 is a top view of the hook for hedge trimmer; and,

FIG. 7 is a bottom view of the hook for hedge trimmer.

The broken lines shown in the drawings illustrate portions of the hook for hedge trimmer that form no part of the claimed design.
